UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

FRUIT-TRAY.

1,289,203.

Specification of Letters Patent. Patented Dec. 31, 1918.

Application filed January 19, 1918. Serial No. 212,762.

To all whom it may concern:

Be it known that I, ALFRED M. LANE, a citizen of the United States, and a resident of the city of St. Louis and State of Missouri, have invented a new and useful Improvement in Fruit-Trays, of which the following is a specification.

This invention relates to trays of the kind used for drying fruits. Its principal objects 10 are to provide for ventilation throughout the entire mass of fruit; to provide for the stacking of one tray on another; to provide for simplicity and cheapness of construction; to make it easy to replace the openwork bottom; and also to provide for taking up slack 15 in the bottom.

The invention consists in the construction hereinafter more fully described and claimed.

In the accompanying drawing wherein 20 like numerals designate like parts wherever they occur,

Figure 1 is a plan view of a tray embodying my invention, with certain portions broken away;

Fig. 2 is a cross sectional view of the marginal portion of the tray illustrated in 25 Fig. 1;

Fig. 3 is a bottom view of the corner portion of the fruit tray shown in Fig. 1; and

Figs. 4, 5 and 6 are cross sectional views 30 of the marginal portion of fruit trays embodying modifications of construction.

Referring to the construction illustrated in Figs. 1, 2 and 3, the body portion of the 35 tray comprises four sections 7 of sheet metal having their ends mitered to constitute the sides and ends of the tray. Their top and bottom margins are curled or beaded; and stiff wire corner pieces 8 are inserted in the 40 meeting ends of adjacent sections to reinforce the corners of the tray.

Each of the side and end sections 7 has a horizontal portion, 9 an upper portion 10 extending upwardly from the inner margin 45 of said horizontal portion and preferably inclined outwardly and a lower portion 12 extending downwardly from the outer margin of said horizontal portion. The horizontal portion 9 thus constitutes an offset or shoulder beneath which extends an open-work bottom, 13, preferably a sheet of wire cloth. This sheet of wire cloth is of greater 50 dimensions than those of the vertical lower portion of the tray so that the marginal portions of said wire cloth are bent to lie

against the vertical lower portion of the tray. Located inside of the bent marginal portion of the wire cloth and extending around the four sides of the tray is a bar or frame 14 which is adapted to clamp the wire 60 cloth in place and reinforce the tray. The ends of this frame are preferably lap jointed at the center of one side as at 16. (See Fig. 1). The bar illustrated in Fig. 2 is screw-threaded and is held in place by means of 65 screws, 15, which extend through the vertical lower portion of the tray and the down-turned portion of the wire cloth, so as to clamp the wire cloth firmly between them. This clamping and reinforcing bar may be 70 of such width that its upper edge binds the horizontal portion of the wire cloth against the horizontal shoulder of the tray.

Preferably the contour of the upper edge of the tray is so much smaller than the 75 contour of the bottom edge that when a multiplicity of similar trays are used, it is possible to pile them, one on another, in stable and convenient stacks. For this purpose the overall dimensions of the upper portion 80 should be less than the dimensions inside of this clamping bar. One of the great advantages of the construction above described is the fact that the wire cloth spans from wall to wall of the tray, in consequence of 85 which the entire contents of the tray are well exposed to ventilation and the device is not as likely to accumulate litter as those devices wherein the marginal portions of the wire cloth rest on an imperforated flange. 90 Another great advantage of this construction is the facility with which the wire cloth may be mounted, dismounted and replaced whenever occasion requires. In order to mount the wire cloth, it is simply necessary 95 to bend it over the outer edge of the clamping and reinforcing bar and then place them in position and secure them by the screws.

The construction illustrated in Fig. 4 is a modification wherein the lower edges of the 100 side and end sections are simply doubled back without other reinforcement and wherein the clamping and reinforcing frame is held by means of bolts 16 which extend inwardly through the ends of the tray sections, 105 wire cloth and clamping and reinforcing frame and are provided with nuts 17 on their threaded inner ends.

Fig. 5 illustrates another modification whose particular merit is the convenience 110

- with which the wire cloth may be tightened in case it becomes slack. In this construction, the portion of the tray sections beneath the horizontal shoulder is formed with a 5 V-shaped shoulder 18 and with rebent horizontal and vertical portions 19 and 20 intended to stiffen the frame. Opposite the V-shaped shoulder on the inner side thereof, is a clamping member made of sheet metal bent 10 into a shape hereinafter referred to as channel-shaped. The longitudinal middle portion 21 of this clamping member is flat and disposed vertically; and its longitudinal side portions 22 are bent horizontally and thence 15 are bent inwardly and backwardly at an inclination as at 23 and are again bent so that their extreme marginal portions are disposed substantially vertically. In this construction, the marginal portion of the wire 20 cloth is looped over the V-shaped rib and the clamping member is placed with its throat opposite the tip of the rib and with its inclined portions 23 bearing against the wire cloth. Horizontally disposed screw bolts 24 25 extending through the tip of the V-shaped shoulder and the base of the channel shaped locking members are provided with nuts 25 on the ends. The particular advantage of this arrangement is that the locking member 30 has a certain resiliency by which it is adapted to spread and ride outwardly on the V-shaped rib thereby taking up the slack in the wire cloth and tightening the same in place.
- 35 The construction illustrated in Fig. 6 is another modification embodying some of the principal features of the construction first above described. In this construction, the lower edges 26 of the sections are simply 40 flanged inwardly; and while this construction is a very simple one, it requires the locking bar or frame to be sprung into position.
- 45 Obviously my invention is not limited to the details of the construction heretofore described.
- What I claim is:
1. A fruit tray comprising walls with an inwardly offset portion and an openwork bottom extending underneath said offset and 50 devices located under said offset portion for securing said bottom without obstructing the opening of the offset.
  2. A fruit tray whose walls comprise a horizontal portion, a portion extending upwardly from the inner margin thereof and a portion extending downwardly from the outer margin thereof, and an openwork bottom extending underneath said horizontal portion and devices located under said offset 55 portion for securing said bottom without obstructing the opening of the offset.
  3. A fruit tray whose walls comprise a horizontal portion, a portion extending upwardly from the inner margin thereof and 60 a portion extending downwardly from the 65

outer margin thereof, and an openwork bottom extending underneath said horizontal portion, the upper portion being small enough to enter the lower portion of a similar tray of the same dimensions.

4. A fruit tray whose walls comprise a horizontal portion, a portion extending upwardly from the inner margin thereof and a portion extending downwardly from the outer margin thereof, and an openwork bottom extending underneath said horizontal portion and having downturned margins 70 75 clamping members inside of said downturned margins but beyond the inner margin of said horizontal portion, and means for securing said members to the lowermost portion of the walls and thereby clamping said bottom in place.

5. A fruit tray whose walls comprise a horizontal portion, a portion extending upwardly from the inner margin thereof and a portion extending downwardly from the outer margin thereof, and an openwork bottom extending underneath said horizontal portion and having downturned margins, 80 85 clamping members inside of said downturned margins but beyond the inner margin of said horizontal portion, and means for securing said members to the lowermost portion of the walls and thereby removably 90 95 clamping said bottom in place.

6. A fruit tray whose walls have a horizontal portion, a portion extending upwardly from the inner margin of said horizontal section and a portion extending downwardly from the outer margin thereof, and an openwork bottom extending under said horizontal portion and a clamping frame insertible and withdrawable through the lower opening of said walls independently of said 100 105 bottom for removably securing said bottom in place.

7. A fruit tray whose walls have a horizontal portion, a portion inclining continuously upwardly and outwardly from the inner margin of said horizontal section and a portion extending downwardly from the outer margin thereof, and an openwork bottom extending under said horizontal portion, and means under said horizontal portion and beyond the inner margin thereof for securing said bottom without obstructing the opening covered thereby.

8. A fruit tray whose walls have a horizontal portion, a portion extending upwardly from the inner margin of said horizontal portion and a portion extending downwardly from the outer margin thereof, and an openwork bottom extending under said horizontal portion and having its margins turned down, and means for securing said bottom, said means comprising a clamping frame insertible and withdrawable through the lower opening of said walls.

9. A fruit tray whose walls have a hori-

zontal portion, a portion extending upwardly from the inner margin of said horizontal portion and a portion extending downwardly from the outer margin thereof, the 5 opening between the lower portion of said walls being greatest at the lower end thereof, and an openwork bottom extending under said horizontal portion, and means insertible and withdrawable through said opening for

removably securing said bottom to the lower 10 portion of said walls, said means being narrow enough to avoid obstructing the opening at the inner margin of the horizontal portion.

Signed at St. Louis, Missouri, this 15th 15 day of January, 1918.

ALFRED M. LANE.
